BOTTLE CARTON

Arthur Rous, New York, N. Y., assignor to Federal
Carton Corporation, New York, N. Y., a cor-
poration of New York

Application March 2, 1938, Serial No. 193,385

3 Claims. (Cl. 229—22)

The object of the present invention is to provide an inexpensive sturdy bottle carton by means of which a plurality, for example, six, liquid-containing bottles may be packaged and carried by means of a handle device adapted as a latching element for the folded carton panels, and this being accomplished by die-cutting a sheet of cardboard without any waste of importance.

The invention will be described with reference to the accompanying drawing in which:—

Figure 1 is a perspective view of an embodiment of the invention.

Figure 2 is a diagrammatic plan view showing three of the cartons placed together to denote the relative position of the cartons in packing them for shipment of bottles in bulk.

Figure 3 is a plan view of the blank.

Figure 4 is a perspective view of an embodiment of the invention, showing the position of the carton elements as the bottles are inserted therein.

Figure 5 is a fragmentary perspective view, showing the upper portion of an embodiment of the invention, with a modified form of latch or locking element.

Referring to the drawing, it will be seen that the device enables the packing of a plurality of bottles in superposed horizontal rows as indicated in Figure 1. The necks of the bottles may extend outwardly through openings in an end panel of the structure and the folded panels enclose the bottles and provide an overlying handle for conveniently carrying the package.

The blank shown in Figure 3 comprises a base panel 1 having at each end a lip 1x provided with a fold line at 1xx. At one side of panel 1 is a multi-panel section scored along the lines a and b to form a central substantially triangular panel 2 at the sides of which are the wings 3 and 3x.

Each wing is formed with a hand hole at 4. At the side of base panel 1 opposite panel 2 is a multi-panel structure scored on the lines a to define a central substantially triangular panel 5 at the sides of which are the wings 6, 6x. Wing 6 is formed with a hand hole at 7 and wing 6x is cut in U-shaped formation to provide a handle latch foldable on the scored line b as later to be described.

In using the device, the lips extending from the sides of panel 1 may be folded upwardly, and then somewhat inwardly along the lines 1xx and thereupon panel 2 may be folded upwardly on the scored line c. The wings may then be bent inwardly a slight distance so that the partially folded structure will lie in the position of Figure 4. Thereupon, three bottles may be moved for-

wardly upon panel 1 so that the necks thereof will project through the lowermost row of neck-receiving apertures, which apertures are indicated at 9. The first row of bottles will afford support for the succeeding two bottles to form a second row, and the final bottle of the half-dozen when placed over between the two underlying bottles. The necks of the bottles will then be projected as in the manner shown in Figure 1. When the bottles are thus stacked the substantially triangular panel 5 is folded upward along the line d and the wings are inwardly bent so that all of the handle holes 4 are brought into mutual contact. At this point, the handle latch 10 carried by wing 6x, which wing lies over wing 3x, as shown in Figure 1, will be pressed through the hand holes and swung upwardly into latching position. Due to the fact that the handle latch 10 has its major length at its central longitudinal line, it will be securely held in position when it is pressed through the hand hole of the panel wing 6. In addition to this locking characteristic, the handle latch serves as a covering face for the hand hole cut into each of the lips h and enables carrying the package without the latter cutting into the fingers. The handle elements above the hand holes are indicated at h.

A modification of the handle lip is shown in Figure 5 at 10x, it being wedge-shape in formation and secured to the abutting handle lips by a staple 11.

The bottles are indicated by the numeral 12 and their caps at 12x. The bottle-containing packages when shipped in bulk may be alternately reversed as shown in Figure 2 and the capped bottles of a lower layer of cartons will give adequate support for an overlaying layer of filled cartons as will be readily understood. In abutting the cartons the handle lips may be folded upon one face of the carton, as shown in Figure 2, in each case.

Having described my invention, what I claim and desire to secure by Letters Patent, is as follows:

1. A carrying carton for bottles comprising a sheet of cardboard or the like formed with a centrally disposed base panel and each side thereof formed with a multi-panel structure scored to define a central substantially triangular panel and a panel wing extending from each side thereof, each panel wing being formed with an outwardly projected handle member and being provided with a hand hole cut, the sheet material within the hand hole cut of one panel wing being adapted to enter the hand hole cuts of the

remaining three wings and to serve as a latching lip to hold the carton in closed position, one of the triangular panels being formed with rows of apertures to receive the necks of bottles contained within the carton.

- 5 2. A carrying carton for bottles comprising a sheet of cardboard or the like, formed with a centrally disposed base panel having laterally projected lips, and at each side of the base panel formed with a multi-panel structure scored to define a central substantially triangular panel and a panel wing extending from each side thereof, one of the triangular panels being formed
- 10

with rows of apertures to receive the necks of bottles contained within the carton, the lips being adapted for movement within the wings of the triangular panels, thereby closing the carton.

3. A carrying carton for bottles constructed in accordance with claim 2, in which the plurality of wings which extend from the sides of the central substantially triangular panels are formed with outwardly projecting handle members adapted to contact and to be mutually held together for maintaining the carton in closed position. 10

ARTHUR ROUS.
